UNITED STATES PATENT OFFICE.

ROBERT W. LINLEY AND PHILLIP B. LINLEY, OF FAIRFIELD, CONNECTICUT.

PRIMING VALVE.

1,421,793.

Specification of Letters Patent. Patented July 4, 1922.

Application filed January 14, 1921. Serial No. 437,314.

To all whom it may concern:

Be it known that we, ROBERT W. LINLEY and PHILLIP B. LINLEY, citizens of the United States, and residents of Fairfield, in 5 the county of Fairfield and State of Connecticut, have invented certain new and useful Improvements in Priming Valves, of which the following is a specification.

This invention relates to priming cups 10 such as are used in connection with gas engine cylinders for the introduction of preliminary charges of fuel.

The object of the invention is to provide an inexpensive and practically constructed 15 priming cup, adaptable to various forms of explosive engines, comprising a reservoir having a cover capable of being positioned to afford a large filling opening or to tightly close the reservoir, a needle valve for regulating the flow of fuel from the reservoir to a gas engine cylinder, a rotatable operating handle for manipulating the needle valve, simply and novelly constructed connections between the needle valve operating handle 20 and the cover whereby the cover can be positioned by rotation of the operating handle to open or close the reservoir.

With the above and other objects in view, the invention resides and consists in the 30 novel combination and arrangement of parts shown in the accompanying drawing forming a part of this specification and upon which,

Fig. 1 is side elevational view of the 35 priming cup;

Fig. 2 is a vertical sectional view thereof;

Fig. 3 is a section on line 3—3 in Fig. 1, looking in the direction of the arrows;

Fig. 4 is a section on line 4—4 in Fig. 1, 40 looking in the direction of the arrows; and

Fig. 5 is a section corresponding with Fig. 4, but showing the cover in open position.

Referring in detail to the reference numerals marked upon the drawing, 10 denotes the main body of the priming valve and 11 the lower threaded plug portion thereof adapted to be screwed into an engine cylinder or otherwise connected therewith 45 as the situation may require. This plug portion 11 includes a drain passage 12 adapted to communicate with a reservoir 13 in the lower portion of which is located the preferably beveled end, denoted by 14, of a 55 needle valve, said beveled end being adapted to engage an annular beveled seat 15

formed in body 10 and surrounding the inlet to drain passage 12 before mentioned. The stem 16 of the needle valve includes a threaded portion 17 adapted to ride in a 60 threaded hub 18 of the valve body to move the beveled end from and toward its seat when the valve stem is rotated, as will be understood. 19 denotes an operating handle fixed in any desired manner upon the outer 65 end of stem 16 and preferably constructed of fiber or other suitable material that will not become hot.

A cover 20, adapted to close the reservoir, is provided with an opening 21 to receive 70 the valve stem or its threaded portion. This cover is capable of being swung upon the valve stem as a pivot to open and close the reservoir by means of the operating handle in the manner now to be explained. A coil 75 spring 22, freely positioned about the valve stem and located between the operating handle and the cover, has its lower portion resting against the upper face of the cover to hold the same firmly upon the valve body 80 and its lower end bent downwardly in about the manner shown to pass through a hole in the cover and to extend downwardly slightly into the reservoir, as denoted by numeral 23, and its upper portion resting 85 against the lower face of the operating handle and its upper end extending outwardly, as denoted by numeral 24, in position to be engaged by a continuous series of protuberances 25 extending downwardly 90 from the lower face of the operating handle and located about the valve stem at a slight distance therefrom.

The method of operation is apparent. Suppose the cover and valve are both in 95 closed position and it is desired to introduce a charge. The operating handle of Figs. 1 and 2 is simply turned in left hand direction. The initial turning movement will, through the instrumentality of the coil 100 spring, cause the cover to open to the position of Fig. 5, the engagement of end 24 with a protuberance 25 furnishing sufficient friction to cause the cover to turn with the stem, as will be evident. When, however, 105 end 23 has engaged the wall of the reservoir, as suggested in Fig. 5, the cover cannot be turned further. Continued left hand turning of the operating handle will cause the beveled portion of the needle valve to 110 recede from its seat, end 24 riding over the protuberances. After the charge has been,

introduced, the operating handle may be turned in right hand direction to first close the cover, the engagement of end 24 with a protuberance providing the necessary friction. When the cover has reached the position of Fig. 4, so that end 23 engages the wall of the reservoir, continued right hand turning of the operating handle causes end 24 to ride over protuberances and the bevelled portion of the needle valve to rest against its seat in the valve body, as is obvious.

Having thus described the invention, what we claim and desire to secure by Letters

15 Patent is:

1. A priming cup including a reservoir, a valve and valve stem having an operating handle, a cover pivoted upon the valve stem and adapted to close the reservoir, and a spring upon the valve stem having one of its ends in frictional engagement with the handle and its other end directly secured to the cover, to open and close the same.

2. A priming cup including a valve body and a valve having a stem, a reservoir in the body, a cover for the reservoir, and connections between the valve stem and cover whereby the cover is frictionally engaged and turned by the stem in a way to open or 30 close the reservoir, said connections permitting a further movement of the valve stem

independent of the cover and comprising a spring frictionally supported from the valve stem, engaging the cover, and adapted to engage the wall of the reservoir.

35

3. A priming cup comprising a body having a fluid passage therethrough, a valve having a stem adapted to open and close the passage, a reservoir located to one side of the valve and connecting with the passage past the valve, a cover for the reservoir and pivoted upon the valve stem, an operating handle fixed upon said stem, a spring upon the valve stem and between the handle and cover, and protuberances upon the handle, said spring having an end secured to said cover and adapted to engage the wall of said reservoir and an end adapted to frictionally engage said protuberances, whereby the cover can be made to turn with the valve stem to open or to close the reservoir and the valve stem can have further turning movement independent of the cover.

Signed at Bridgeport in the county of 40
Fairfield and State of Connecticut this 7th 45
day of January A. D., 1921.
